UNITED STATES PATENT OFFICE.

LYNDALL O. HANSON, OF NEW AUBURN, WISCONSIN.

PIPE HOIST.

Application filed May 6, 1924. Serial No. 711,420.

To all whom it may concern:

Be it known that I, LYNDALL O. HANSON, a citizen of the United States, residing at New Auburn, in the county of Chippewa and State of Wisconsin, have invented certain new and useful Improvements in Pipe Hoists, of which the following is a specification.

The present invention relates to a pipe hoist implement and has for its prime object to provide a device of this nature which may be easily engaged with a pipe such as extends downwardly in a well in order that the same may be conveniently lifted therefrom.

Another important object of the invention is to provide a hoist of this nature embodying a strong and durable structure which is efficient, reliable, and well adapted to the purpose for which it is designed.

With the above and numerous other objects in view as will appear as the description progresses, the invention resides in certain novel features of construction, and in the combination and arrangement of parts as will be hereinafter more fully described and claimed.

In the drawing:

Figure 1 is a perspective view showing the implement embodying my invention engaged with a pipe section,

Figure 2 is a fragmentary plan view of the bar showing particularly the headed end thereof,

Figure 3 is an elevation of the structure shown in Figure 2 a portion thereof being shown in section taken substantially on the line 3-3 of Figure 2,

Figure 4 is a detail perspective of the jaws, and

Figure 5 is a detail section through the hooked end of the lever.

Referring to the drawing in detail it will be seen that the device consists of a bar A and a lever B pivoted thereto. The bar A is provided with an elongated shank 1 one head headed as at 2 provided with a V-shaped recess 3 having a pair of pockets 4 therein for receiving the removable jaws 5 one face being provided with transversely extending corrugations 6. Each jaw is provided with an apertured ear or lug 7 extending rearwardly therefrom and embedded into the headed end 2 of the shank 1 in order that screws 8 passing through the headed end 2 may also engage the apertures

of the lug to hold the jaws in place and assembled as is indicated in Figure 2.

The lever B is pivoted intermediate its ends as at 9 to an intermediate portion of the shank 1 adjacent the head 2. The shank of this lever is substantially Z-shaped so as to include an intermediate portion 10, the handle 11, and the arm 12. This arm 12 is provided with a hooked end 13 the interior face of which is corrugated as is shown to advantage in Figure 5.

The implement is engaged with a pipe section as is indicated to advantage in Figure 1 so that the hooked end 13 of the lever B is disposed below the headed end 2 of the bar A. It will thus be seen that by lifting upwardly on the bar A the pipe may be readily lifted from the well. It is advantageous to utilize two of these implements. It will readily be seen that by pushing downwardly upon the handle 11 as the device is shown in Figure 1 the jaw formed by the hook end 13 may be released from the pipe section in order that the implement may be slipped downwardly in order to grip the pipe at a lower point. By using two of these implements the pipe may be easily released from the well since the device is easily manipulated and the structure is so simple that there is nothing which could readily become out of order.

Although I have described the invention with a certain degree of particularity, it is evident that changes in the details of construction, and in the combination and arrangement of parts may be resorted to without departing from the spirit or scope of the invention as hereinafter claimed or sacrificing any of its advantages.

Having thus described my invention, what I claim as new is:

An implement of the class described including in combination a bar and a lever pivoted intermediate its ends to an intermediate portion of the bar, said bar including an elongated shank, a head formed on one end of the shank, a jaw associated with the head, said lever including an intermediate portion, a handle extending from one end of the intermediate portion at an angle thereto, an arm extending from the other end of the intermediate portion and terminating in a hook extension having interior corrugations.

In testimony whereof I affix my signature.

LYNDALL O. HANSON.
